[57] CLAIM

The ornamental design for a booklet slip cover, as shown and described.

DESCRIPTION

FIG. 1 is a perspective view of a booklet slip cover showing my new design;

FIG. 2 is a left side elevational view thereof;

FIG. 3 is a right side elevational view thereof;

FIG. 4 is a top plan view thereof;

FIG. 5 is a bottom plan view thereof;

FIG. 6 is an enlarged right edge elevational view thereof;

FIG. 7 is an enlarged left edge elevational view thereof;

FIG. 8 is a perspective view showing the booklet slip cover in open position with a booklet mounted therein shown in broken lines;

FIG. 9 is an elevational view showing the outside of the booklet slip cover in open position;

FIG. 10 is an elevational view showing the inside of the booklet slip cover in open position with a booklet mounted therein shown in broken lines;

FIG. 11 is an enlarged left edge elevational view of the booklet slip cover in open position with a booklet mounted therein shown in broken lines;

FIG. 12 is an enlarged right edge elevational view of the booklet slip cover in open position with a booklet mounted therein shown in broken lines;

FIG. 13 is an enlarged top plan view of the booklet slip cover in open position with a booklet mounted therein shown in broken lines; and,

FIG. 14 is an enlarged bottom plan view of the booklet slip cover in open position with a booklet mounted therein shown in broken lines.

The portions shown in broken lines in FIGS. 8 and 10 through 14 are for informational purposes only and form no part of the instant design.
